UNITED STATES PATENT OFFICE.

GEORGE L. BALLARD, OF NORRISTOWN, PENNSYLVANIA, ASSIGNOR TO WILDMAN MFG. CO., A CORPORATION OF PENNSYLVANIA.

KNITTING-MACHINE.

1,247,615.

Specification of Letters Patent. Patented Nov. 27, 1917.

Application filed November 26, 1915. Serial No. 63,582.

To all whom it may concern:

Be it known that I, GEORGE L. BALLARD, a subject of the King of Great Britain, residing at Norristown, Pennsylvania, have invented certain new and useful Improvements in Knitting-Machines, of which the following is a specification.

Needle cylinders, as ordinarily constructed, are provided with slots for guiding the reciprocating needles, the said slots being formed by cutting or milling them directly in the wall of the cylinder. This practice is objectionable because in hardening the cylinders the walls between the slots are liable to get out of true relation and affect the perfect guidance of the needles. It has been proposed heretofore to provide needle cylinders with inserted walls for the needle grooves or slots, and my present invention relates to this general form of needle cylinder. By the use of the inserted walls the hardening of the body portion of the cylinder may be dispensed with, the walls alone being hardened before insertion into the cylinder, and thus providing guiding surfaces sufficiently hard to withstand the wear.

The present invention consists in the features of construction and arrangement and combination of parts hereinafter described and particularly defined by the appended claims.

In the accompanying drawings;

Figure 1 is a sectional view of a part of a needle cylinder and sinker or web holder dial with my improvements combined therewith;

Fig. 2 is a view of one of the lower inserted walls or strips which may be of hardened material to withstand the wear of the sliding needles, or needles and jacks;

Fig. 3 is a side view of one of the upper needle wall members; and

Fig. 4 is a front elevation of a portion of the needle cylinder;

Fig. 5 is a view showing another form of certain of the devices;

Fig. 6 is a view similar to Fig. 1 of another form of the invention;

Fig. 7 is a view of a group of elements belonging to Fig. 6.

In these drawings, the needle cylinder is shown at 1 having attached thereto by screws 2 the ring 3 having the gear 4 formed thereon, by which the cylinder is ro-

tated. It will be understood, however, that my invention is not limited to that type of machine in which the cylinder rotates. The ring 3 bears in a frame ring 5, which has the ring or plate 6 connected therewith which, in turn, supports the cam cylinder. The needles may be either of the latch type or the spring beard type. Surrounding the upper portion of the needle cylinder is a dial or ring 11 in which are guided sinkers, web holders or like instruments. The needle guiding walls, instead of being formed directly or integrally with the main body of the cylinder by deeply slotting said cylinder, are provided by lower pieces or strips 15, and by upper pieces or plates 16. The lower members 15 of the cylinder walls fit within shallow grooves of the cylinder indicated by the dotted lines 17 in Fig. 1, the said walls being sufficiently wide to project from these shallow grooves to afford guidance for the heels of the needles, or for the needles and jacks. The said wall members 15 are provided at their lower ends with beveled projections 18 fitting between the bottom of the shallow grooves of the cylinder, and a beveled rim or flange 19 formed on the clamp ring 3' which is secured to the bottom of the cylinder by screws 3'. The upper ends of these lower wall sections are provided with beveled projections 18' which are engaged by downwardly extending beveled projections 20 of the upper wall sections 16. These upper wall sections are provided with projections 22 on their inner edges which fit into a circumferential groove 23 near the top of the cylinder, and these upper wall sections have their upper ends 24 terminating just below the slots 25, 25' in the cylinder and dial or ring which supports the radially movable instruments. The upper wall sections 16 have wider central portions 26, and as shown in Fig. 1 the sinker or web holder dial 11 rests upon the shoulder or upper edge of these upper wall sections at 27, and thus these wall sections serve as hangers for supporting the sinker or web holder dial.

Removably attached to the main portion or ring 11 of the sinker or web holder ring 105 is a ring 11' secured by screws 28. This ring is beveled on its inner side at 29, and bears against a correspondingly beveled edge of the upper wall section serving to firmly seat and clamp the upper wall sec-

- 6 tions to the cylinder. From this construction it will be seen that portions of the 10 sinker dial or ring embrace the laterally or radially projecting wider portions of the upper wall members, and as these wall members are hung to the cylinder and are held against vertical displacement, the dial is securely held in place, and as just stated, the dial or rather the lower ring 11^a thereof 15 by the wedging effect of the beveled surface 20 serves to force the wall sections to and hold them in place. The lower wall sections 15 may be made of hardened material to withstand the wear due to the thrust of the needle cams against the needle jacks, or against the needles if needles are employed without jacks, whereas the upper wall sections need not be hardened, as the wear against these is not sufficient to necessitate hardening.
- 20 By making the needle wall of the upper and lower sections as described, the lower sections can be removed and replaced when worn without disturbing the upper wall sections or the sinkers, web holders, or the dial 25 therefore.
- 25 In renewing any of the lower wall sections the screws 2 may be removed, and the cylinder lifted away from the ring 3, and access can thus be had to the lower wall sections 30 for their removal and replacement.
- 30 The needles may be held in place by spring bands and the upper wall sections are provided with recesses 32 to accommodate these bands.
- 35 It will be seen that the lower wall sections will be wedged into place and clamped in the cylinder grooves because of the beveled edges of the upper wall sections and the upper ends of the sections 15 and because 40 of the form of the lower ends of said sections 15 and the ring 3'. I prefer to provide the lower wall sections with fulcrum points at α to bear on the bottom of the groove in the cylinder so that in placing 45 these walls in position their upper beveled ends are engaged under the beveled lower edges of the upper wall sections 16 and then by swinging the said walls inwardly on the points α as fulcrums and by seating the 50 lower beveled ends of the walls within the beveled ring 19 and screwing the parts together the walls 15 will be firmly seated and clamped. In this fulcrum action the lower ends of the upper sections will spring 55 or yield sufficiently to the movement of the upper ends of the lower sections.
- 55 The needle cylinder may have its grooves cut in the ordinary manner clear through from top to bottom.
- 60 By reason of the fulcrum and the beveled 65 contacting edges at the upper end of the inserted walls 15, some pressure is necessary to swing the inserted walls against their seats in the cylinder grooves and the action 70 of the beveled contacts at the said lower

ends of the walls 15 is to wedge said walls upwardly. It will be observed also that the contact between the lower wall sections 15 and the upper wall sections 16 takes place at a point below the plane of the clamping ring 70 11^a that is to say the upper wall has a portion depending below the point where wedging or clamping pressure is exerted thereon by the encircling ring and it is with this depending portion that the wedging action 75 takes place upon the lower wall sections.

I show in Fig. 5 a modification in which the beveled or wedge construction is not present and while such construction is practical, I prefer to employ that first described. 80

In Figs. 6 and 7 I show sections of the cylinder wall substantially like those 15 and 16 before described, and the needle cylinder is mounted on the gear ring 3 in a manner substantially similar to that shown in Fig. 5, 85 that is to say, the lower edge of the cylinder fits inside a flange or rib 3^a in the gear ring. The needle guiding walls 15^x, however, terminate at a point above the lower edge of the cylinder, and their lower inclined edges 90 are borne upon by a ring 19^x inclined on its inner or upper face to fit the incline of the edges of the walls.

This ring is of a diameter to fit against the outside of the cylinder and below the 95 grooved portion thereof. The ring is pressed upwardly and held by screws 3^b which are held in the lower edge of the cylinder and which have their heads adapted to engage and press upwardly upon the ring 19^x, and thus press the needle walls 15^x upwardly and inwardly to clamp them against the cylinder and against the wall sections 16. There may be three of the screws or more or less, as desired, and the cylinder is counter-bored at 30 to receive them. 105

The needle cylinder is secured to the ring 3 by screws such as shown at 2, Fig. 5, and there may be three of these alternating with the screws 3^b. By this construction the needle cylinder is centered entirely independent of the means employed to clamp the walls in place. This centering is due to fitting the cylinder within the flange or rib 3^a and securing it by the screws 2. 110

I claim as my invention:—

1. In combination with a needle cylinder having shallow grooves, lower wall sections for guiding the needles seated in said shallow grooves, a ring engaging the lower ends 120 of said lower wall sections and removably attached to the cylinder, upper needle guiding wall sections having their lower ends interlocked with the lower wall sections to hold them in place, said needle cylinder having a circumferential groove, and said upper wall sections having a portion fitting in said groove, and means for holding the said upper wall sections in engagement with said groove, substantially as described. 125

2. In combination with a needle cylinder, needle guiding walls composed of upper and lower sections, said lower sections being removably held to the needle cylinder, partly by the upper wall sections, and a sinker or web holder dial surrounding the upper wall sections and holding them to the needle cylinders, substantially as described.
3. In combination with a needle cylinder having shallow grooves, needle guiding walls inserted in said grooves, and composed of lower and upper sections interlocking with each other, said needle cylinder having a circumferential support engaged by the upper needle wall sections, said upper needle wall sections having shoulders, a web holder or sinker dial supported on said shoulders and surrounding the said upper needle wall sections to hold them in connection with the needle cylinder, and means for holding the lower ends of the lower needle wall sections to the cylinder, substantially as described.
4. In combination with a needle cylinder having shallow grooves, needle guiding walls formed of upper and lower sections seated in said grooves, said needle cylinder having a circumferential groove near its upper end and the said upper needle wall sections having projections entering said grooves and having their lower ends interlocked with the lower needle wall sections, means for holding the lower ends of the lower needle wall sections to the needle cylinder, a sinker or web holder dial supported on the upper needle wall sections, and a ring removably secured to the lower side of the said dial and engaging from below the lower needle wall sections, substantially as described.
5. In combination with a needle cylinder, an inserted needle wall section having a projection entering a circumferential groove in the cylinder, and having notches for spring bands, and also having a projection to interlock with lower needle wall sections, said projections supporting the wall section independently of the lower wall section, substantially as described.
6. In combination a needle cylinder, a bed surrounding said cylinder, needle walls removably carried by the said cylinder, said bed being supported on the needle walls, instruments guided in the bed, and a ring removably secured to the lower side of said bed and engaging parts of the said removable walls for clamping them in place, substantially as described.
7. In combination a needle cylinder having a circumferential groove, needle walls having projections entering said groove and supported on said outwardly extending portions, a bed supported on said outwardly extending portions and surrounding the said walls, and instruments working in said bed, the said walls terminating at a point below the lower edge of the said instruments, substantially as described.
8. In combination a needle cylinder, needle guiding walls inserted therein, and interlocking therewith and a web holder or sinker dial or ring surrounding said inserted walls and having a beveled portion to engage the inserted walls and wedge them to their seats, substantially as described.
9. In combination a needle cylinder, needle guiding walls inserted therein, a sinker or web holder ring composed of sections clamping between them portions of the inserted walls and one of said sections having an inclined face to wedge the inserted walls against their seats in the cylinder, substantially as described.
10. In combination a needle cylinder, needle guiding walls inserted therein, a dial or ring for holding and guiding sinkers or web holders, said ring being supported by the inserted walls, and a ring adjustably attached to the lower face of the said dial or ring, and having an inclined face acting upon the inserted walls to wedge them to their seats in the cylinder, substantially as described.
11. In combination with a needle cylinder, needle guiding walls inserted therein and composed of upper and lower sections, the inwardly beveled upper ends of the lower sections fitting under the downwardly and outwardly inclined ends of the upper sections, means for holding the upper sections in the cylinder and means for holding the lower ends of the lower sections, said means having a wedge face engaging a corresponding face of the lower sections to wedge the lower sections inwardly and upwardly and causing their upper ends to be wedged under the lower ends of the upper sections.
12. In combination with a needle cylinder, inserted walls composed of upper and lower sections, interlocking at their meeting ends by the upper end of the lower section fitting between the lower end of the upper section and the needle cylinder, said lower section having a fulcrum point thereon bearing on the cylinder, means for holding the lower end of the lower section, substantially as described, and means for holding the upper sections to the cylinder against the fulcrum action of the lower sections.
13. In combination a needle cylinder, upper and lower wall sections seated therein, said lower section engaging the inner side of portions of the upper wall sections and fulcruming on the cylinder at a point below said upper ends and means for holding the lower ends of the lower wall sections, said upper wall sections having free depending

- ends carrying said engaging portions, with means above said ends for holding the upper sections in place, substantially as described.
5. 14. In combination a needle cylinder, a support on which the needle cylinder rests, means for connecting the cylinder with said support removably, removable needle guiding walls carried by the cylinder having 10 inclined lower ends, a ring having an incline corresponding to the incline of the lower ends of the needle walls and screws

seated in the lower end of the cylinder above the support and having heads reaching out under the said ring to adjust it vertically when the screws are turned, substantially as described. 15

In testimony whereof, I affix my signature in presence of two witnesses.

GEORGE L. BALLARD.
